UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF SAME PLACE.

DESIGN FOR A RUG.

SPECIFICATION forming part of Design No. 33,938, dated January 22, 1901.

Application filed December 29, 1900. Serial No. 41,537. Term of patent 3½ years.

To all whom it may concern:

Be it known that I, ADOLPH PETZOLD, a citizen of the United States, residing at Philadelphia, in the State of Pennsylvania, have 5 invented and produced a certain new and original Design for a Rug, of which the following is a full, clear, and exact description, reference being had to the accompanying drawing, forming a part of this specification.

10 My design has relation to the surface ornamentation of a woven rug. It is delineated in plan view in said drawing, and its distinguishing and characteristic features are the central rectangular line-figure A, inclosing 15 and forming a plain field-center, and surrounding the same in border-like form is a floral ornamentation consisting of a series of side wreaths B and corner wreaths B' with a bunch of flowers C opposite each side wreath and an extreme outside border consisting of 20 a series of connected small floral figures D.

I claim as new and of my invention—

The design for a rug, substantially as shown and described.

In testimony whereof I have hereunto affixed my signature this 24th day of December, A. D. 1900.

ADOLPH PETZOLD.
